UNITED STATES PATENT OFFICE

FRANK MEESE, OF CHICAGO, ILLINOIS

LEAD AND RULE CUTTER

Application filed November 23, 1929. Serial No. 409,257.

This invention relates to improvements in lead and rule cutters. One object is to provide a lead and rule cutter that is accurate in operation. A further object is to provide a 5 lead and rule cutter that is positive and efficient in operation, one in which the measurements taken can be instantly read thereby greatly facilitating the work in hand, and a machine that is compact in assembly but so 10 constructed that extra long measurements can be readily taken.

With the foregoing and other objects in view the invention consists in the combination and arrangement of parts to be herein- 15 after fully described, pointed out in the claims and illustrated in the accompanying drawings which form a part of this application for patent and in which—

Fig. 1 is a view of the machine in side elevation.

Fig. 2 is a top plan view of the machine.

Fig. 3 is an end view of Fig. 1.

Fig. 4 is a fragmentary view, enlarged, of one end of the gage and frame.

Fig. 5 is a cross section on the line 5—5 of Fig. 4.

Fig. 6 is a view in cross section, enlarged, on the line 6—6 of Fig. 2.

Fig. 7 is a similar view on the line 7—7 of Fig. 2.

Fig. 8 is a fragmentary plan view of the machine.

Like reference characters denote corresponding parts throughout the several views.

The lead rules and cutters now in general use have their gages provided with teeth or notches. These teeth or notches do not provide a true or accurate measurement due to the fact that they are measured off, when made, to provide approximate measurements only. The present lead and rule cutter is provided with a screw shaft in which the threads take the place of the notched bar of the ordinary gage.

This screw shaft is accurately cut and the resulting measurements are necessarily absolutely correct.

The reference numeral 1 denotes the frame provided with feet 2 and comprising an arch 3 and formed with a transverse ledge 4 to

receive the bed 5. The frame is formed, adjacent one end of the bed, with a recess 6 that registers with a similar recess 7 in the bed whereby to form a socket for the stationary blade 8. The frame and bed are secured together by the screws 9 and by loosening the same slightly the blade 8 may be inserted into, adjusted, or removed from its socket, no screws or other fastening means being necessary for the blade.

A bolt 10 extending through the frame, at one foot of the arch, serves as a fulcrum for the knife bar 11 provided with the movable blade 12, said knife bar being connected by the coil spring 13 to the arch 3 whereby to yieldingly retain said bar and blade in raised position. To lugs 14 secured to the knife bar a link 15 is secured by pin 16, said link being secured by pin 17 to side lugs 18 riveted to the hand lever 19 fulcrumed upon the bolt 20 to the arch of the frame, said hand lever being formed with a spur 21 against the end of which one end of the link 15 abuts, thus taking the strain of operation of the handle off the pin 17. As the hand lever is moved back and forth upon its fulcrum the movable knife and the knife bar oscillate, the knife passing close beside the stationary blade and cooperating with the same to cut the work in hand.

The bed 5 is formed with a longitudinally extending slot 22 that runs from end to end and upon opposite sides of said slot the longitudinal recesses 23, 24 are formed that are parallel to said slot.

A hollow gauge 25 of the same length as the bed 5 is formed with one lateral open face 26 and is adapted to slidably rest upon the said bed, said gauge being formed with a depending rib 27 that extends through the slot 22 and has a bar 28 secured thereto by pins 29 below the said slot 22, said rib and bar serving to slidably secure the gauge to the bed. A lug 30 secured to the forward end of the gauge rides in the said groove 23 to prevent very thin stock from slipping under the forward end of the gauge as it is moved over the bed.

A screw shaft 31 extends from end to end of the gauge and is operatively supported in the ends thereof, one end extending through

the gauge end to receive the cap 32 having the knurled head 33 by means of which it may be rotated.

The cap and head 32, 33 are the only means of rotating the screw shaft. The pitch of the screw threads is such that one complete revolution of the screw shaft will advance the gauge along the bed a distance of six points, printer's standard measurement. A clamp 34 secured by screws 35 to the bed operatively houses a Z-shaped lever 36, the lower end of said lever extending outwardly from the bed and receiving one end of the expansion coil spring 37, housed in said clamp, whereby to 10 yieldingly retain said lever in depressed position. The upwardly and inwardly extending end of said lever is shaped to releasably engage the threads of the screw shaft to lock said gauge against sliding movement over the bed. Due to the lever 36 the screw shaft is made operable to actuate the gauge only through oscillation or rotation of the said cap and head 32, 33.

The upper face of the gauge is graduated in ems and ens, printer's standard measurement and is readable in connection with the indicator 38 upon the uppermost face of the bracket 34 and indicates the distance between the forward or inner end of the gauge and the cutting edge of the knife blade 8.

It will be noted that there are two rows 38' and 38a of ems and ens upon the top face of the gauge, one row along each lateral edge.

Pivotedly secured to the closed lateral face 35 of the gauge by the pin 39 is the extension arm 40 provided at its free end with the laterally extending integral head 41 which is formed with diametrically opposed recesses 42 and, spaced therefrom, with similarly opposed ribs 43, 43. The length of the extension arm from the center of its pivot pin 39 to the relatively outer face of the head 41 is such that, in the position of this arm and head shown in Fig. 7, the head 41 is flush with the adjacent end of the gauge and therefore the distance from the cutting edge of the knife blade 8 to the head 41 is the same as the distance from the said knife edge to the end of the gauge.

When the head 41 is turned to its position nearest the knife the reading is taken from the indicator along the line of graduations contiguous thereto. This reading shows the distance from the head 41 to the cutting edge 55 of the knife.

When the extension arm is thrown 180 degrees about its pivot the distance from the inner face of the head 41 to the cutting edge of the knife 8 is exactly twice the distance from the inner end of the gauge to the said knife edge, provided the gauge is then disposed the maximum distance from the frame 1. Provided the gauge is only slid away from the frame 1 a part of the maximum distance 60 possible a reading from the inner face of the

head 41 to the cutting edge of the knife 8 will be shown by the indicator 38 in connection with the relatively remote line of graduations upon the gauge. One lateral edge of the extension arm is formed with a recess 44 for engagement, in the outer position of said arm, with the pin 39 to prevent lateral or downward movement of said arm through gravity. The recesses 42 in head 41 are to receive the rib 45, in either extreme position of said arm upon its pivot, and to provide clearance for said rib, this rib serving as a guide for the stock being cut.

The ribs 43 of the head travel in the groove 24 and prevent thin stock, that is being cut, from wedging under the head. The rib 45 is spaced inwardly upon the bed from the knife 8 to provide clearance for stock that may be laid across the bed at right angles to the rib.

Fulcrumed to the under part of the frame upon the pin 46 is a handle 47, of spring steel, provided with a knob 48, said handle carrying a pin 49 adapted for engagement with either of the recessed portions 50 of said frame whereby to yieldingly keep said handle in either of two adjusted positions relative to said frame. In Fig. 6 the handle is shown in raised position. At the forward end of said handle it engages a pin 51 that extends vertically through a perforation in the bed 5 in line with the rib 45 but spaced therefrom. By means of the handle 47 the pin may be projected above the surface of the bed or withdrawn to a position flush therewith. This pin serves in conjunction with the rib to guide the stock to the knife for the cutting operation.

When it is desired to slide the gage along the bed the lower outwardly bent end of the Z-lever 36 is manually pressed upwardly, against the tension of the spring 37, to cause the upper inwardly bent end of the lever to release the screw shaft. The gauge may now be moved freely to the desired position. When it is desired to move the shaft but the distance of one half point, or at most not more than an em, the cap and head 32, 33 are rotated. The cap is preferably divided off into 12 equal parts by the graduations 52. One complete revolution of the screw shaft advances the gauge six points and, therefore, turning the cap a distance of one notch will advance the gauge one half point.

The stock to be cut is laid upon the bed against the rib 24 and pin 51 as guides, one end of the stock abutting the head 41. When the lever 19 is manually depressed it causes the knives 8, 12 to cut the stock.

When stock is to be trimmed or cut down to suit the height of type it is placed transversely of the bed, the pin 51 being depressed, the stock abutting the head 41 and contiguous end of the gauge.

What is claimed is:—

1. In a lead and rule cutter, a frame, a bed detachably secured thereto, a stationary knife

- carried by said bed, an oscillating knife carried by said frame for cooperation with said stationary knife, a gauge adjustably carried by said bed, and an extension for said gauge 5 pivotally connected thereto and adjustable therewith upon said bed.
2. In a lead and rule cutter, a frame, a bed detachably secured thereto, a stationary knife carried removably and jointly by said bed and 10 frame, an oscillating knife carried by said frame for cooperation with said stationary knife, a graduated gauge adjustably carried by said bed and readable in connection with the cutting edge of said knife, and an extension 15 element for said gauge pivotally secured thereto and being readable in connection therewith.
3. In a lead and rule cutter, a frame, a bed detachably secured thereto, a stationary knife 20 carried by said bed at its juncture with said frame, an oscillating knife carried by said frame for cooperation with said stationary knife, a graduated gauge slidably carried by said bed and readable in connection with the 25 cutting edge of said knife, and an extension element pivotally secured to said gauge and slidable upon said bed, said extension element being readable in connection with said gauge and, in one position of said gauge, showing a 30 reading exactly twice that of said gauge.
4. In a lead and rule cutter, a frame, a bed detachably secured thereto, a stationary knife carried by said bed at its juncture with said frame, an oscillating knife carried by said 35 frame for cooperation with said stationary knife, a graduated gauge adjustably carried by said bed and readable in connection with the cutting edge of said knife, and an extension element pivotally secured to said gauge 40 and slidable upon said bed for cooperation with said gauge; said extension in one position of said gauge disclosing a reading exactly twice that of said gauge and at other positions of said gauge upon the bed disclosing 45 readings materially greater than said gauge reading.
5. In a lead and rule cutter, a frame, a bed detachably secured thereto, a stationary knife carried by said bed at its juncture with said 50 frame, an oscillating knife carried by said frame for cooperation with said stationary knife, a graduated gauge slidably and adjustably carried by said bed, a screw shaft carried by said gauge, a cap at one end of said 55 screw shaft for actuating the same, a lever releasably connecting said bed and screw shaft whereby the latter is normally locked against movement other than that imparted through said cap, and an extension pivotally 60 secured to said gauge and readable in connection therewith.
6. In a lead and rule cutter, a frame, a bed detachably secured thereto, a stationary knife carried by said bed at its juncture with said 65 frame, an oscillating knife carried by said
- frame for cooperation with said stationary knife, a gauge adjustably carried by said bed and formed with two rows of graduations, an indicator for said gauge, an extension for said gauge pivotally secured thereto, said indicator being readable in connection with one row of graduations to determine the distance from one end of said gauge to the cutting edge of the stationary knife and readable in connection with the other row of graduations to 70 determine the distance from the free end of said extension element and said cutting edge.
7. In a lead and rule cutter, a frame, a bed detachably secured thereto, a stationary knife 75 carried by said bed at its juncture with said frame, an oscillating knife carried by said frame for cooperation with said stationary knife, a guide rib for said bed, said bed being formed with longitudinal recesses upon opposite sides of said rib, a gauge adjustably arranged upon said bed, an extension therefor pivotally secured thereto, said extension comprising a head, said head being recessed to afford clearance for said rib, ribs formed upon 80 said head for engagement with one of the longitudinal recesses of said bed, a lug for said gauge riding in the other longitudinal recess of said bed, and a manually adjustable pin movable through said bed contiguous to 85 said stationary knife and located in a straight line connecting the same and said guide rib.
- In testimony that I claim the foregoing as my own I have hereto affixed my signature.
